UNITED STATES PATENT OFFICE

166,532

COMBINED CHEST AND TELEPHONE STAND, OR SIMILAR ARTICLE

George E. Edler, Halls, Tenn.

Application October 16, 1951, Serial No. 16,959

Term of patent 3½ years

(Cl. D33—14)

To all whom it may concern:

Be it known that I, George E. Edler, a citizen of the United States and resident of Halls, in the county of Lauderdale and State of Tennessee, have invented a new, original, and ornamental Design for a Combined Chest and Telephone Stand or Similar Article, of which the following is a specification, reference being had to the accompanying drawing, forming a part thereof.

In the drawing, Figure 1 is a perspective view of a combined chest and telephone stand or similar article, showing my new design with the telephone stand folded in the chest;

Figure 2 is a similar view showing the telephone stand in extended position; and

Figure 3 is a longitudinal sectional view showing the stand folded in the chest and with the cover open.

I claim:

The ornamental design for a combined chest and telephone stand or similar article, as shown.

GEORGE E. EDLER.
